UNITED STATES PATENT OFFICE.

WILLIAM E. LUDLOW, OF CLEVELAND, OHIO.

CALENDAR.

1,124,926.

Specification of Letters Patent.

Patented Jan. 12, 1915.

Application filed March 28, 1913. Serial No. 757,387.

To all whom it may concern:

Be it known that I, WILLIAM E. LUDLOW, a citizen of the United States, residing at Cleveland, in the county of Cuyahoga and State of Ohio, have invented a certain new and useful Improvement in Calendars, of which the following is a full, clear, and exact description, reference being had to the accompanying drawings.

10 This invention relates to a calendar of the type in which the numeral indicating the date is changed each day by means of a suitable motor.

One of the objects is to provide a simple, 15 compact calendar, which operates, upon the closing of an electric circuit, to bring successively into view numerals indicating the day of the month, the numeral shown being comparatively much larger with respect to 20 the device than in mechanically operated calendars used heretofore.

To accomplish this I provide a calendar which utilizes a ribbon of suitable length, on which are arranged numerals indicating 25 the days of the month, there being a motor for moving the ribbon to bring the numerals successively into view whenever released by the action of an electro-magnet, or by hand. The mechanism by which I 30 carry this out, as well as various features contributing to the efficiency of the operation, constitute the present invention, as will become apparent in the following description and claims.

35 Referring to the drawings, Figure 1 is a side elevation of the mechanism with one side of the casing removed; Fig. 2 is a detail of one of the spools on which the ribbon is wound and the mechanism for operating 40 it; Fig. 3 is an end elevation of the driving mechanism, the near end of the casing being sectioned substantially on the line 3—3 of Fig. 1; Fig. 4 is a transverse section taken substantially on the line 4—4 of Fig. 45 1; Fig. 5 is a detail of one of the brakes on one of the spools carrying the ribbon; Fig. 6 is a perspective of the device, showing a convenient, compact casing and the position 50 of the numeral indicating the day of the month.

10, in the drawings, indicates a suitable casing for my device, which is closed at the top and bottom and on the four sides. One side, however, is an opening 11, which is 55 covered by a suitable pane of glass 12, through which are seen the numerals indi-

cating the days of the month. Suitably journaled at its ends in the plates 14 and 15 is a shaft 18, on which is rigidly secured a spool 19, which is the feeding spool for the 60 ribbon 20, on which are marked the numerals indicating the days of the month. This spool is preferably made tubular for lightness, and has at each end a flange 21. A second spool 25 is carried on a shaft 26, 65 suitably journaled at each end in the plates 14 and 15. This spool is similar to the spool 19 and has corresponding flanges 28 adapted to guide the ribbon.

Suitable rollers 29 and 30 are carried on 70 shafts extending between the plates 14 and 15 and journaled at their ends in these plates. These rollers 29 and 30 are positioned near the front side of the casing 10 and guide the ribbon to bring it near the 75 glass 12. The shaft 26, which carries the spool 25, is engaged by flanged bearings 32 carried on the ends of the spool and is keyed to one of these flanges 32 by a small key 33, which is slidable in this flanged 80 bearing.

The spool 25 is adapted to be driven by a suitable spring motor to wind the ribbon 20 on to it and off from the spool 19. This motor, indicated at 35, is a spring motor of 85 the type ordinarily used in clocks, and is carried by the plate 14. As shown, this motor has a spring 36 adapted to drive a gear 37, which, in turn, drives a train of gears comprising a pinion 37^a, a gear 37^b, a 90 pinion 37^c, a gear 37^d, and a pinion 37^e and a gear 37^f, and lastly a pinion 37^g carried on the arbor which has a revolving fan to control the speed of the motor. These gears and pinions are carried on suitable arbors, 95 which are journaled in two plates 39 and 40, comprising the sides or frame of the motor.

On the lower end of the plate 40 is secured a small plate 41, which has a bearing in axial alinement with the shaft 26. Journaled at one end in this bearing is a short shaft 43 carrying a small gear 44 rigid therewith and in engagement with the large gear 37. The other end of this shaft 43 is reduced in diameter and is journaled in a 105 suitable bracket 45 made of a U-shaped piece of flat metal secured to the plate 14. The reduced end of the shaft 43 carries a small key 46 inside the bracket 45, which engages a suitable key way in an enlarged end 110 of the shaft 26. Thus, when the gear 37 is rotated by means of the spring 36, the shaft

43 will be rotated by means of the gear 44 and the shaft 26 will be driven by means of the key 46 engaging the key way in the end of the shaft 26, and, accordingly, the spool 19 will be rotated and will wind up a definite amount of the ribbon 20.

On the end of the shaft 43 adjacent the plate 41, is a circular disk 48 having a notch 49 in its periphery. A lever 50 is pivoted 10 at 51 to the plate 40 and carries a flat finger 52, which is adapted to ride on the periphery of the disk 48 and drop into the notch 49 whenever this notch comes under this finger 52. Pivotedly attached to the lever 50 at 15 53 is a rod 54 extending vertically adjacent the plate 40 and guided by a suitable bracket 55, through which it passes, this bracket 55 being secured to the plate 40 at its upper corner. Secured to the upper end of this 20 rod 54 is a short L-shaped arm having one portion substantially in the plane of the plate 40, and another portion, indicated at 57 in Figs. 1 and 3 at substantially right angles to this plate 40.

Carried on the arbor which carries the pinion 37^g is an arm 59 adapted, at times, to engage the stop 57 carried by the rod 54. When the lever 50 is raised, as shown in the drawings, the projection 52 is raised out 25 of the notch 49 and the spring 36 is permitted to rotate the disk 48 and the arm 59, as described. As the disk is rotated with the shaft 43, the spool 25 is also rotated. To raise the lever 50 by closing an electric circuit, I have provided a magnet 60 having a pivoted armature 66 having an extension 67 30 engaging a notch 68 in the lever 50. This notch has one sloping side, as shown, and, whenever the armature 66 is drawn toward the magnet, the lever 50 will be cammed to 35 its raised position shown in Fig. 3.

When the spool 25 has made one revolution, the notch 49 will again be brought under the finger 52 and the lever 50 will 40 drop, causing the rod 54 and the stop 57 to drop also, bringing the stop 57 into the path of the end of the arm 59. The engagement of the arm 59 with the stop 57 stops the motor and takes the strain off the finger 52.

As shown, the magnet 60 is mounted on a 45 plate 70, having suitable binding posts 71 to which the wires leading to the magnet are attached. Made solid with this plate 70, is an arm 73 leading upwardly and then 50 diagonally toward the plate 14, to which it is secured at 74. The bottom or lower edge of this plate 70 is shown as secured to an angle piece 75 carried on the bottom of the casing 10.

Carried on a suitable platform 76 secured 60 to the plate 15 at one edge and resting upon an upright member 77, which, in turn, rests upon the bottom of the casing, is a battery 78 which supplies the current for energizing the magnet 60. Leading from this bat-

tery 78 to the magnet 60, are wires 80 and 81, shown diagrammatically in Fig. 1. On the wire 81 is a suitable switch adapted to close the circuit to energize the magnet, and, as shown, it is of the type of the ordinary 70 push button. This switch is shown in section in Fig. 2 and has a contact plate 85 and a spring contact 86 adapted to be pressed against the plate 85 by means of a plunger 88 carried in the casing 89. This switch 75 may be located at any convenient point, and is usually distant from the casing; it is shown on the casing for convenience of illustration. It will be seen that whenever the circuit is closed through the magnet and 80 the armature 66 drawn toward the magnet the lever 50 will be moved upwardly, permitting the disk 48 to rotate one revolution.

The spool 25 is preferably made of such a diameter that its effective circumference 85 will be equal to the distance required to bring the next numeral indicating the date 90 into view. That is, as the spool is rotated once, it will wind up enough ribbon to move one of these numerals away from the opening 11, and bring the next one into view, and the numerals are spaced by slightly increasing amounts to compensate for the effective enlarging of the spool as the ribbon 95 winds onto it.

Thus it will be seen that to use this calendar satisfactorily, it is only necessary to 100 close the circuit to operate the mechanism once a day. After thirty or thirty-one operations, the ribbon will all be wound from the spool 19 to the spool 25, having shown each of the days in succession throughout the month. Then, to rewind the calendar to begin a month, the shaft 26 is disconnected from the shaft 43 and the spool 19 rotated 105 by hand.

As heretofore stated, the shaft 26 is made 110 slideable in the journals 32 of the spool 25, and the key 33 is adapted to slide in its key way in one of the journals 32. The shaft 26 is engaged by the key 46 on the shaft 43, and may be moved to slide off from this key by pulling the shaft lengthwise of the spool 25. At the opposite end, the shaft 26 has a 115 reduced diameter 90 and a head 92 adjacent to this neck. A yoke 93 in the form of a box having two sides open, has one side journaled on the neck 91 and engaging the head 92. Carried rigid on the other side is a threaded extension 95 in axial alignment with the shaft 26. Screwed on to the end of this extension 95 is a plunger 96 to which is pivotally attached a lever 97. A plate 98 having a bearing 99 for the plunger 96 has also a suitable support for the pivot 100 of the lever 97. Now, when the lower end of the lever 97 is pressed toward the casing, the plunger 96 and the yoke 93 and the shaft 26 are moved to the right and the shaft 26 is thereby drawn out of engage- 120 125 130

ment with the key 46 on the shaft 43, thus permitting this spool 25 to rotate freely. A flexible metal strip 101 may be secured to the bottom of the casing 10 and extend 5 through the yoke 93 to prevent its turning with the shaft 26. On the inside of the spool is a spring 102 surrounding the shaft 26 and engaging the pin 103. This spring 102 is adapted to press the shaft 26 toward 10 the shaft 43 to keep the key 46 in engagement with its key way.

The shaft 18 of the spool 19 is extended at one end and carries a pin 105, which may be engaged by a slot in the socket of a suitable crank-wrench 106. After the shaft 26 is disengaged from the shaft 43 the crank 106 is inserted so that it engages its pin 105 and the spool 19 is then rotated by means of the crank 106, to wind back the ribbon 20 15 from the spool 25 to the spool 19 until the numeral 1 is brought in front of the glass 12 indicating the first day of the month.

In order that the ribbon 20 may be stretched tightly between the rollers 29 and 25 to present a neat appearance, I have provided brakes on the spool 19 so that, as the ribbon is drawn from this spool to the spool 25, it will be kept taut. These brakes comprise brake-drums 107 carried on the ends 30 of the spool 19. Bearing against these brake drums are brake shoes 108 (Fig. 5), each having a curved surface engaging the drum 107, and held pressed against this drum by means of a suitable spring 109. The tension 35 of this spring 109 may be changed by a suitable adjusting screw 110 threaded through a clip 111 carried by the upper edge of the plates 14 and 15.

In case it becomes necessary to trip the 40 motor mechanism by hand, I have provided a pin 112 carried by a lever 114 suitably pivoted at 115 to the end of the casing 10. The pin 112 extends through a suitable slot 45 in the end of the casing, and one end stands over the end of the lever 50 to the right of the pivot 51, so that, when this pin 112 is depressed it will press downwardly on the end of the lever 50 and raise the finger 52 from the notch in the disk 48. This lever 50 is indicated in dot and dash lines in Fig. 3.

It will be seen from the foregoing description that I have provided a neat, compact calendar showing a large size figure,

and one which may be adapted for many practical uses. It is adapted, for example, 55 to be placed high on a wall, or in other comparatively inaccessible places, as it only needs rewinding once a month.

My device is particularly well adapted to be used in office buildings and hotels where 60 any number of calendars may be arranged on one circuit, and each morning an attendant may close this circuit and operate all of the calendars to bring fresh numerals into view. 65

Having thus described my invention, what I claim is:

1. The combination of a casing, a pair of spools therein having shafts, a ribbon running from one spool to the other, a motor 70 mechanism adapted to engage the shaft of one of the spools to wind the ribbon off of the other spool, a yoke engaging a groove in the last named shaft, a spring finger secured to the casing extending into the said 75 yoke to prevent the rotation thereof, and a lever mounted on the outside of the casing for drawing the shaft of the driven spool longitudinally to disconnect it from the motor, whereby the ribbon may be wound back 80 on the other spool.

2. The combination of a casing, a pair of spools therein each having a shaft, a ribbon running from one spool to the other, a motor mechanism adapted to engage the shaft of 85 one of the spools to wind the ribbon off from the other spool, a yoke engaging the groove in the shaft of the last-mentioned spool, a spring finger secured to the casing and extending into said yoke to prevent the rotation thereof, a plunger mounted in the casing and threaded to said yoke, a lever mounted on the outside of the casing and attached to said plunger for drawing the driven spool longitudinally to disconnect it 90 from the motor, whereby the ribbon may be wound back on the other spool, and a spring on the shaft of the driven spool tending to press the shaft into engagement with its driving means. 95

In testimony whereof, I hereunto affix my signature in the presence of two witnesses.

WILLIAM E. LUDLOW.
